United States Patent Office.

ISRAEL L. LANDIS, OF LANCASTER, PENNSYLVANIA.

Letters Patent No. 73,016, dated January 7, 1868.

IMPROVEMENT IN FARM-GATES.

The Schedule referred to in these Letters Patent and making part of the same.

TO ALL WHOM IT MAY CONCERN:

Be it known that I, ISRAEL L. LANDIS, of the city of Lancaster, county of Lancaster, and State of Pennsylvania, have invented an "Improved Farm-Gate;" and I do hereby declare the following to be an exact description thereof, reference being had to the accompanying drawings, and to the letters of reference marked thereon, making a part of this specification.

The nature of my invention consists in an upright spring-lever (attached to the latch of the gate) near the centre of the gate, operated by rope and pulleys, and a cross-rail, set diagonally across the gate, for the purpose of raising the front part of the gate.

Figure 1 is a perspective view of the gate, and
Figure 2 exhibits the hinge.

A A A A represent four posts; B, the gate, that is attached to the centre posts A A by hinges C C, the hinges being bent so as to form an aperture, D, at the bend, to fit on to a staple, E, in the hind post A. A wooden block, F, fits into the centre of the hinge, to stay the hinge, and strengthen its position between the rails G and G and uprights H H, at the rear end of the gate, by means of bolts, J J, passing through the uprights H, rails G, and hinge C. All the rails G of the gate operate on pivot-bolts at their rear ends. K is an upright lever, on the one side of the gate, near its centre, operating on a pivot, L, at its lower end, braced by a clip, M, and having a flat spring, N, to throw the lever forward, that is attached to the latch P at R, to close or shut the latch, by which means the latch is self-acting, to fasten the gate when closed. At the upper end of the lever K the rope S is fastened, and passes around the pulleys T on the top rail of the gate, and extends on each side to the arms U U, on the outer posts A A, over pulleys V V, with a handle, W W, at each end, when, by pulling at either handle, W W, the lever K draws back the latch, and the gate is drawn back by the rope, and opened or closed at either side, the latch catching into the groove or either of the posts. A rail operating as a lever, X, works on a pivot, Y, at the lower end, and a clip, Z, at the upper end, on the upper rail G of the gate, and as the upper end of the rail X (which rests diagonally across the gate) is raised, the front end of the gate is raised to any required height, and is held in its position by a pin, passing through apertures or pigs to pass under, or to open and close free of snow in the winter.

What I claim as my invention, and desire to secure by Letters Patent, is—

1. The upright lever K, its spring N, clip M, and latch P, when arranged, combined, and operated by the rope S and pulleys T, as herein described, and for the purposes set forth.
2. I also claim the construction and combination of the bent hinge C with its inside block F, as herein described, and for the purposes set forth.
3. I also claim the diagonal rail X, with its clip Z, when combined and operated with the upper rail G of the gate, as herein described, and for the purposes set forth.
